CLAIM

The ornamental design for a photographing device as shown and described.

DESCRIPTION

FIG. 1 is a perspective view of a photographing device showing my new design;

FIG. 2 is a front view thereof;

FIG. 3 is a rear view thereof;

FIG. 4 is a left view thereof;

FIG. 5 is a right view thereof;

FIG. 6 is a top plan view thereof;

FIG. 7 is a bottom plan view thereof;

FIG. 8 is a perspective view of the photographing device when the monitor is in an unfolded position; and,

FIG. 9 is a top plan view of the photographing device when the monitor is in the unfolded position.

The broken lines in the drawings depict portions of the photographing device that form no part of the claim.

1 Claim, 9 Drawing Sheets
